UNITED STATES PATENT OFFICE.

HERMANN HOFFMEISTER AND EDMUND FRIEDRICH, OF MEIDLING, AUSTRIA.

ATMOSPHERICAL STEAM-ENGINE.

SPECIFICATION forming part of Letters Patent No. 239,955, dated April 12, 1881.

Application filed October 25, 1880. (No model.) Patented in Austria January 23, 1879.

To all whom it may concern:

Be it known that we, HERMANN HOFFMEISTER and EDMUND FRIEDRICH, both of the city of Meidling, in the Empire of Austria, have 5 invented a new and useful Atmospherical Steam-Engine, of which the following is a specification.

Our invention relates to improvements in single - acting atmospherical steam - engines, 10 more particularly intended for family use; and the objects of our improvements are, first, to provide a new mechanism for distributing the steam directly by the piston; second, the automatic water-supply, also by the piston; and, 15 third, an in explosive steam - generator. We obtain these objects by the mechanism illustrated in the accompanying drawings, in which—

Figure 1 is a vertical longitudinal section of 20 the machine; Fig. 2, a plan of the heating mechanism; Fig. 3, a plan of the entire machine; Fig. 4, a vertical cross-section of the same; Fig. 5, a horizontal section of the cylinder with the piston, and the Figs. 6 to 10 25 show the positions of the entry and outlet openings of the steam during the ascent and descent of the piston.

Similar letters of reference indicate similar parts in all the figures.

30 The engine consists of an in explosive steam-generator, A, and a cylinder, B, open at one end, in which the piston C works, distributing the steam, and at the same time regulating the water-supply. To the machine belongs, further, 35 a surface-condenser or water-tank, E, provided with a serpentine pipe, G', through which the exhaust-steam passes.

The steam is generated in small brass pipes, n n, and on the top and the side walls of that 40 part of the fire-box F which projects into the steam-generator A.

Small motors are heated by gas, petroleum, &c., and larger ones by coal, coke, wood, &c.

The top of the box F, which forms the bottom 45 of the steam-generator A, is made from a round corrugated sheet, a, of steel, which is bulged more or less by the pressure of the steam in the generator, and regulates thereby the supply of gas to the burner D by opening 50 or closing the valve b. This valve b is so regulated that when the motor stops only the necessary quantity of gas or other vapor or fluid

is allowed to pass, sufficient to maintain the desired steam-pressure.

On the top of the piston C a projection, C', 55 is provided, with a suitable opening in which a cam, d', on the shaft d works. During the motion of the piston C and shaft d the action of the cam d' will cause this projection C', and consequently the piston C, to turn sidewise 60 from one side to the other and back.

In one side of the piston C a groove, e, (see Figs. 4 and 5,) is made, which, in consequence of the above-mentioned turning of the piston, will, during the ascent of said piston, be before 65 the inlet f, and during the descent of the piston before the steam-outlet g. This groove e is shortened on the side of the inlet, (see Figs. 6 to 10,) whereby the necessary expansion or the desired amount of cut-off is obtained.

Figs. 6 to 10 show the positions of the openings and this groove during the ascent and descent of the piston. Fig. 6 shows the beginning of the steam-supply and ascent of the piston. In Fig. 7 the piston C is just in the 75 middle of its stroke. Fig. 8 shows the beginning of the expansion. The inlet-opening f is just closed. Fig. 9, the piston is in its highest position, or at its top stroke. In the next moment the action of the cam d' will turn the 80 piston C, bringing the groove e before the outlet-passage g. Fig. 10 shows the piston at half-stroke, descending, and the outlet g entirely open.

The exhaust-steam passes through the pipe 85 G into the serpentine pipe G' in the water-tank E, and then into the collecting-box m, where the condensed water is collected. This box m serves to collect the condensed water and to equalize the supply of the feed-water. On top 90 of the box m a small air-valve, h, is provided. The condensed water passes from the box m through a pipe, H, to a chamber, J, in the cylinder, and from there into a groove, K, or recess made in the piston C. During the descent 95 of the piston the groove K comes opposite to a chamber, L, likewise arranged in the cylinder B, and this condensed water escapes thus into this chamber L, back into the steam-generator A. The groove or recess K will be filled with 100 steam each time after the water has been discharged, but this steam is condensed by the contact with the fresh supply of feed-water passing through chamber J. It will thus be

seen that the steam passing at one side from the generator A to operate the piston is brought back as condensed water at the other side to the steam-generator.

5 The vacuum produced below the piston after the escape and condensation of the steam serves, in connection with the atmospheric pressure upon the top of the piston, to move the same downward.

10 *p p p p* are outlets for the heated gases from the fire-box F.

The joint of the connecting-rod *s* is made movable in its turning-pin *r*, to allow for the turning of the piston in the manner and for 15 the purpose above described.

What we claim as our invention, and desire to secure by Letters Patent, is—

1. In combination with cylinder B, pitman S, and shaft *d*, the piston C, having a slotted 20 upper extension or frame, and grooved to engage alternately with the inlet and exhaust ports of said cylinder, the cam *d'*, carried by said shaft and turning in said slotted extension or frame, whereby a vibratory as well as 25 a reciprocatory motion is imparted to said piston, for the purpose set forth.

2. In an atmospheric steam-engine, the cylinder B, provided with a chamber, J, connected with a feed-water chamber, *m*, and with a chamber, L, connected to the top of the steam-generator, in combination with a piston, C, provided with a recess or cavity, K, arranged to operate substantially in the manner and for the purpose specified. 30

3. In an atmospheric steam-engine, the combination of the steam-generator A, burner D, having its supply automatically regulated by the steam-pressure, the cylinder B, with cavities L and J, the vertically-moving piston C, provided with recess K and groove *e*, and projecting frame C', operated by a cam, *d'*, and the exhaust-pipe G and feed-water pipe H, and the condensing-tank E, the whole being constructed and arranged to operate in the manner and for the purpose herein described and 40 specified. 45

HERMANN HOFFMEISTER.
EDMUND FRIEDRICH.
